(57) **CLAIM**

The ornamental design for a quick release plate with mobile phone tripod, as shown and described.

DESCRIPTION

FIG. 1 is a front, right and top perspective view of a quick release plate with mobile phone tripod showing our new design.

FIG. 2 is a rear, left and bottom perspective view thereof;

FIG. 3 is a rear elevational view thereof;

FIG. 4 is a front elevational view thereof;

FIG. 5 is a left view thereof;

FIG. 6 is a right view thereof;

FIG. 7 is a top plan view thereof;

FIG. 8 is a bottom plan view thereof;

FIG. 9 is a front, right and top perspective view thereof, showing a half-folded configuration;

FIG. 10 is a front, right and top perspective view thereof, showing a full folded configuration;

FIG. 11 is a rear, left and bottom perspective view thereof, showing a full folded configuration;

FIG. 12 is a top plan view thereof, showing a full folded configuration;

FIG. 13 is a bottom plan view thereof, showing a full folded configuration;

FIG. 14 is a right view thereof, showing a full folded configuration;

FIG. 15 is a left view thereof, showing a full folded configuration;

FIG. 16 is a front elevational view thereof, showing a full folded configuration; and,

FIG. 17 is a rear elevational view thereof, showing a full folded configuration.
